CLAIM

The ornamental design for the six-pack holding and cooling system, as shown and described.

DESCRIPTION

FIG. 1 is a front elevational view of the six-pack holding and cooling system showing my new design;

FIG. 2 is a rear elevational view thereof;

FIG. 3 is a side elevational view thereof, the opposite side being identical in appearance;

FIG. 4 is a top plan view thereof;

FIG. 5 is a bottom plan view thereof; and,

FIG. 6 is a plan view of the six-pack holding and cooling system depicted in its open position showing my design.
